UNITED STATES PATENT OFFICE

OSCAR E. NEWBAUER, OF ROCHESTER, NEW YORK

HACK SAW

Application filed September 30, 1931. Serial No. 565,948.

This invention relates to improvements in hack saws of the kind having detachable or interchangeable blades and employed for sawing metal parts.

5 The principal object of the invention is the provision of a saw of this kind having a frame provided with simple and convenient means for conveniently storing blades not in use.

10 Another object of the invention is the provision of a saw frame of this kind having a saw blade receptacle or magazine in its back and a simple and convenient closure for said receptacle.

15 Still another object of the invention is the provision of a saw frame having a blade magazine with simple means for ejecting blades therefrom.

To these and other ends, the invention consists in the construction and arrangement of parts that will appear from the following description when read in conjunction with the accompanying drawings, the novel features being pointed out in the claims at the 25 end of the specification.

In the drawings:

Fig. 1 is a side elevation of a hack saw constructed according to one embodiment of the invention;

30 Fig. 2 is a fragmentary view in side elevation of the back part of the frame showing the closure for the magazine in partly open position;

Fig. 3 is an enlarged section taken substantially on line 3—3 of Fig. 2 and looking in the direction of the arrow at said line;

Fig. 4 is an enlarged section taken substantially on line 4—4 of Fig. 1 and looking in the direction of the arrow at said line, and

40 Fig. 5 is a similar view on line 5—5 of Fig. 1.

Similar reference numerals refer to the same part in all the figures of the drawings.

The invention is illustrated applied to a 45 hack saw of usual or common construction, comprising a frame having a back 1, from the ends of which the arms 2 and 3 project in the same plane. Bosses or sockets 4 and 5 are provided on the ends of the arms 2 and 50 3 in which blade engaging or supporting

members 6 and 7 are or may be slidably mounted. The members 6 and 7 may be provided with studs 8 and 9 for cooperation with openings provided therefor adjacent the opposite ends of a saw blade 11. The member 55 6 may project through the socket 4 and at its outer end may be provided with a handle 12 arranged to engage the outer end of the socket 4 and limit the inward movement of the member 6 therein. The member 7 projects through the socket 5 and is threaded on its outer end for cooperation with a butterfly nut 13 which engages the outer end of the socket 5 and is operative to adjust the member 7 toward or from the member 6 or to vary 60 the tension on a saw blade 11 mounted on and between said members.

65 The back 1 of the frame is preferably formed of sheet material bent on itself to form a U-shaped channel, as more clearly 70 shown in Figs. 3 and 4. The end members or arms 2 and 3 of the frame are arranged to project into the open ends of the channel and secured to the back member by any suitable means, such as rivets as shown. The channel 75 opens upwardly or away from a blade mounted in the frame and is of a length somewhat greater than the length of the longest blade capable of being mounted in the frame and preferably of a width sufficient to receive a 80 plurality of saw blades.

85 It will be noted that the U-shaped back member is closed at its ends to provide a magazine or receptacle for saw blades, and means are provided for closing the open upper side thereof. To this end, a cover or lid 14 is provided. The cover is also U-shaped in cross-section and of a width to fit over the sides of the channel member to which it is pivoted at 15. The cover 14 extends throughout the length of the channel member, and interengaging means, such as the detents 16, 90 may be provided on the cover and channel member for retaining the cover in closed position on the channel member.

95 It is desirable to provide means for conveniently disengaging the detents to separate the free end of the cover from the channel member. To this end, an ejector is provided in the form of a lever 17 pivotally 100

mounted between the walls of the channel member and projecting outwardly therefrom at one end over the adjacent arm 3 which may be cut away as shown at 18 to provide a clearance therefor. The outwardly projecting end of the ejector forms a finger piece, and its other end projects inwardly between the sides of the channel and under the end of the cover 14 when the latter is in closed position. 5 By pressing the outer end of the ejector, its inner end is moved outwardly and moves the cover with it and disengages its detents and moves it from the channel member. 10

Resilient means are provided for throwing 15 or lifting the cover from the channel member when the detents are disengaged. To this end, a leaf spring 19 is secured to the cover at one end, as at 20, by means of a rivet or other suitable device. The spring 19 20 is arranged between the side walls of the cover and curves outwardly from its fixed end and then inwardly between the side walls of the cover into engagement with the cover. When the cover is closed, the spring engages 25 any saw blades arranged in the magazine, which engagement moves the spring into the cover and tensions it between the cover and the saw blades in the magazine. By this arrangement, when the cover is released from 30 the magazine by the finger piece 17, the spring reacts to swing the cover from the magazine. It will also be noted that by its engagement with the saw blades in the magazine, the spring serves to hold them against 35 movement therein when the cover is closed.

When a plurality of saw blades are arranged at one time in the magazine, difficulty is experienced in removing a selected saw blade therefrom. To overcome this difficulty, means are provided for ejecting or lifting 40 one end of the blades from the magazine so that any selected blade may be removed therefrom. To this end, the side walls of the magazine are provided with vertically arranged slots 21 in which an ejector is slidably mounted. Said ejector comprises a pin or rod 22 arranged in said slots and having enlarged or headed ends which engage the outer walls of the magazine and retain it therein. 45 The ejector is preferably arranged adjacent that end of the magazine which is adjacent the free end of the cover and so that the blades in the magazine rest thereon, as seen in Fig. 50 3 of the drawings. By moving the ejector in its slots from the Fig. 3 position, the saw blades contained in the magazine are lifted therefrom and any selected blade may be removed. 55

60 Although only one embodiment of the invention is shown and described herein, it will be understood that this application is intended to cover such changes or modifications as come within the spirit of the invention or scope of the following claims. 65

I claim:

1. A hack saw comprising a frame having a hollow back member open along one of its longitudinal sides, a cover pivoted thereto adjacent one end, and means for detachably 70 securing the cover at its other end.

2. A hack saw comprising a frame having a hollow back member open along one of its longitudinal sides, a cover pivoted thereto adjacent one end, means for detachably securing the cover at its other end, and hand operated means for detaching the cover at 75 said other end.

3. A hack saw comprising a frame having a hollow back member open along one of its longitudinal sides, a cover pivoted thereto adjacent one end, means for detachably securing the cover at its other end, hand operated means for detaching the cover at said other end, and resilient means for swinging the cover to open position when detached 80 from said securing means. 85

4. A hack saw comprising a frame having a hollow member having an open side and adapted to receive blades, a closure therefor, and resilient means on said closure adapted to engage blades in said hollow member and retain them against movement therein. 90

5. A hack saw comprising a frame having a hollow member having an open side and adapted to receive blades, a closure therefor, and means movably mounted in said hollow member for ejecting blades therefrom. 95

6. A hack saw comprising a frame having a hollow channel member having an open side and adapted to receive blades, and an ejector slidably mounted in the walls of said member and movable toward said open side and engageable with blades in said channel member for lifting them therefrom. 100 105

In witness whereof, I have hereunto signed my name.

OSCAR E. NEWBAUER.
